UNITED STATES PATENT OFFICE.

FREDERICK A. HART, OF NEWARK, NEW JERSEY, ASSIGNOR, BY MESNE ASSIGNMENTS, TO UNDERWOOD COMPUTING MACHINE COMPANY, OF NEW YORK, N. Y., A CORPORATION OF NEW YORK.

COMBINED TYPE-WRITING AND COMPUTING MACHINE.

1,186,512.

Specification of Letters Patent.

Patented June 6, 1916.

Original application filed December 10, 1908, Serial No. 466,836. Divided and this application filed September 16, 1914. Serial No. 861,935.

To all whom it may concern:

Be it known that I, FREDERICK A. HART, a citizen of the United States, residing in Newark, in the county of Essex and State of New Jersey, have invented certain new and useful Improvements in Combined Type-Writing and Computing Machines, of which the following is a specification.

My invention relates to computing machines and is herein disclosed as applied to a combined typewriting and computing machine of the Underwood-Hanson type which is of the general form disclosed in the United States patent to Hans Hanson, No. 816,319, dated March 27, 1906, and Nos. 905,421 and 905,422 dated December 1, 1908. In said machine, the numeral keys of the typewriter when operated in the adding zone are caused to set up pins on computation bars which 20 pins and bars may be designated as preliminary representation devices, there being one pin set up on each bar, the pin corresponding to the digit written, and the rack bar corresponding to the letter-space in the travel of the typewriter carriage. When a 25 number has thus had all of its digits set up, it is carried into computing wheels by means of a general operator which includes a cross bar that comes forward, strikes the ends of the depressed pins and carries forward the computation bars by means of said pins thereby turning the computing wheels.

The present invention is especially directed to preventing overthrow of the computation bars by the general operator. If these bars are properly arrested, there is little danger of overthrowing the computing wheels because the computing wheels are constantly engaged by spring detents and 40 said detents tend to arrest their wheels at the proper place, and they will return them from a slight overthrow.

The stroke of the general operator is always the same but the amount to which it 45 will turn the various computing wheels depends on the pins depressed. The rack bars are usually arrested by a stop which intercepts the depressed pins. To avoid accidents it is advantageous to have a stop for arresting the computation bars by their pins, which is normally out of the path of any pins accidentally depressed, and of any other parts, but which becomes effective just at

the moment when it is desired to arrest the computation bars. To this end, I have arranged that the stop shall normally stand clear of the computation bars and other parts, but as the general operator approaches the end of its forward stroke, said stop is swung into position by a cam on the general operator, so that it will intercept the ends of the depressed pins. 55

Other features and advantages will hereinafter appear.

This application is a division of my application No. 466,836, filed December 10, 1908. 65

In the accompanying drawings, Figure 1 is a sectional side view of an Underwood-Hanson combined typewriting and computing machine, showing my invention as applied thereto. Fig. 2 is a section of the computing mechanism proper on a larger scale. Fig. 3 is a fragmentary sectional view taken from the side opposite to Fig. 2. 70

In the Underwood typewriting machine, numeral keys 5 and alphabet keys 4 depress their key levers to cause said levers to swing type-bars 3 upwardly and rearwardly against the platen 14 mounted in the traveling carriage 2, so that the type on said type-bars will print on the work-sheet on the platen. The typewriter carriage travels as the numeral keys are operated, being fed along by the usual escapement devices which include a rack bar 2^b and dogs 2^c which are operated by the usual universal bar 2^d. As the typewriter carriage travels through the adding zone, the numeral keys thereof are caused to set up digits representing numbers on computation bars c, said bars being normally in ineffective position, but in the adding zone being raised one at a time into effective position, so that they will be within range of pin-setting bars b^e, with the result 80 that when any numeral key is depressed, the pin-setting bar b^e which moves therewith, will depress a corresponding pin c^f on the raised computation bar c, said pin representing the digit printed by that numeral key. The computation bars c are shown in their normal position in Fig. 1 and they are raised therefrom one after another by a dog f, which is mounted on the typewriter carriage. Said dog f, to do this, raises one 85 after another jacks f^g, said jacks being piv- 90

oted to a bar f^{18} with result that the rear ends thereof will depress the rods f^{15} . Said rods are connected to the computation bars c , by levers f^{16} in which the bottoms of the 5 rods f^{15} rest, and the levers raise the bars c by lugs f^{20} on transposition linkages f^{23} . The connections are such that the right-hand lever f^{16} raises the left-hand bar c , and so on in reverse order. This is possible 10 because the levers f^{16} are of varying length so that each operates only its own linkage f^{23} , and the lug f^{20} for the left-hand bar c is on the linkage operated by the right-hand lever f^{16} , and so for the others in reverse 15 order. When a computation bar is thus raised, the depression of any numeral key will carry down its pin-setting bar b^7 with the result that said pin-setting bar will strike the proper pin c^8 on the bar c , and 20 depress said pin, so that the lower end of said depressed pin will extend below the bottom of the bar c to a distance shown in Figs. 2 and 3. When a series of pins have thus been depressed, one pin on each bar, a 25 cross-bar c^9 forming part of a general operator is moved forwardly by means of a handle c^{13} , and strikes the ends of the depressed pins carrying the computation bars c forward, thereby causing the computing 30 wheels a to be turned by said bars. For so turning said wheels, the front ends of the bars c are provided with racks which mesh with pinions a^1 connected to the computing 35 wheels a . On the return stroke of the general operator, a second cross bar c^{10} forming part of said operator, strikes lugs c^8 on the computation bars c thereby returning the bars to their normal position. The bars do 40 not turn the computing wheels a on their return stroke, because of pawl and ratchet connections between the pinions a^1 and the wheels a , said connections not being shown herein.

The handle c^{13} moves the general operator 45 by means of a segment c^{14} fast to the shaft c^{12} on which the handle c^{13} is fast, said segment meshing with an idle pinion c^{16} , which pinion in turn meshes with the rack bar c^7 forming part of the general operator, there 50 being a rack bar c^7 and pinion c^{16} on each side of the machine. The rack bars c^7 and the cross bars c^9 and c^{10} form a rigid frame for the general operator. Before beginning 55 a new computation, all of the pins are reset by the handle c^{13} through connections not material in the present invention.

The numeral wheels are normally held 60 by spring detents a^6 . Their carry-over devices, which include pinions a^{10} and a power driven shaft a^{14} connected to the general operator, may be of the same general construction as is disclosed in the Hanson patents aforesaid.

In order to prevent overthrow of the computation bars c on the forward stroke of the 65

general operator, the depressed pins of said bars are automatically intercepted by a stop bail t^3 which normally lies in its downmost ineffective position seen in Fig. 1. When the general operator comes forward, said bail is moved to its effective position seen in Figs. 2 and 3, wherein it is raised adjacent the computation bars c , so that it lies in the path of the bottom ends of the depressed pins. To thus raise it, the general operator 70 is provided with a cam t^9 formed as an extension of a plate t^8 fast to the side rack c^7 of the general operator, said cam being adapted to raise said bail in the interval between a depressed pin and the pin next in 75 front thereof. When said bail is thus raised, the computation bar c is positively caught at the end of the computing operation between said bail and the cross bar c^9 of the general operator, as shown from one 80 side in Fig. 2 and from the opposite side in Fig. 3, wherein the pin representing the digit 9 is shown as depressed.

The bail t^3 is raised to its effective position by the cam t^9 through the tappet t^4 , which latter is fast on a rock shaft k^5 , extending part way across the machine and supported in lugs extending from the frame 85 of the machine. The bail t^3 in order that it may be moved by said shaft is held fast 90 thereto by arms t^4 , and said arms are comparatively long and have a short swing, so that the thrust thereon is nearly horizontal. Thus the arresting of the bars c thereby, has 95 practically no tendency to raise them by rotation of the shaft k^5 .

One result of having the bail t^3 normally in ineffective position is that the rack bar is 100 always arrested by the rearmost pin thereon. This is advantageous because if two pins were accidentally depressed, the general operator would drive said bar by the rearmost depressed pin, while if the stop bail t^3 were fixed in position, it would arrest 105 the rack bar c by the front depressed pin thereon. The driving of the rack bar by one pin, and the arresting of it by another in such a case, might either wreck the machine 110 or cause the computation to be meaningless, since there are usually several rack bars 115 driven by their pins at each computation. Such a result is made impossible by having the bail t^3 normally in ineffective position and raised to effective position only after 120 the pin next the one driven by the general operator has come to where the bail t^3 should stand.

When a number is computed consisting of several digits, such as 381, it will be understood that as the general operator moves forward the cross-bar c^9 engages first the pin corresponding to the digit 8 on the tens rack bar and begins to move the same forward. It next encounters the pin corresponding to the digit 3 on the hundreds rack bar and 125

moves it forward, finally picking up the rack in units order and moving it forward one space. At the time the rack bar in units order is picked up, the pins 3, 8 and 1 on 5 their respective rack bars are in alinement, and during the interval between the picking-up of the units rack bar and the end of its stroke, the general operator brings into action the overthrow-preventing bail ¹³. It 10 will be understood, of course, that the rack bar having the lowest digit value set thereon will be the last one picked up. It will also be clear that when the locking bail becomes effective, all of the pins constituting 15 the number being computed, are in alinement.

Variations may be resorted to within the scope of the invention, and portions of the improvements may be used without others.

20 Having thus described my invention, I claim:

1. In a computing machine, the combination with reciprocating rack bars comprising settable pins, of computing wheels 25 driven by the racks on said rack bars, a reciprocating general operator for driving said bars, and a stop normally in ineffective position but adapted to be swung by said general operator to effective position to arrest 30 said bars by said pins.

2. In a computing machine, the combination with computing wheels, of reciprocating rack bars for driving said wheels, pins settable on said rack bars, a general operator for driving said rack bars by said pins when set, a stop for engaging the set pins to positively arrest the rack bars, said stop normally out of the path of said pins, and means to enable such engagement between 40 said stop and the set pins to take place.

3. In a computing machine, the combination with computing wheels, of rack bars for driving said computing wheels, a source of power for driving said rack bars, a general operator driven by said source of power 45 for so driving them, pins settable on said rack bars to be engaged by said general operator for driving the rack bars, a stop normally in ineffective position, and means for raising said stop to effective position as the pins engaged by the general operator approach it to cause said stop to arrest said rack bars by said pins.

4. In a computing machine, the combination with computation racks and digit pins settable thereon, of a bar standing across 55 the racks and adapted to be moved to drive the racks by the set pins, a stop extending across the racks for engaging the set pins but normally in ineffective position, and means for shifting said stop to effective position to intercept the projecting pin after the next adjacent pin has cleared said stop.

5. In a computing machine, the combination with computation racks and digit pins

settable thereon, of a bar standing across the racks and adapted to be moved to drive the racks by the set pins, a stop extending across the racks for engaging the set pins but normally in ineffective position, and a cam moving with said cross bar for shifting said stop to effective position to intercept the projecting pin after the next adjacent pin has cleared said stop. 70

6. In a computing machine, the combination of computing devices, of actuating means therefor, one for each computing device, said actuating means having pins settable thereon to determine the differential movement of said devices, means for moving 75 the actuating means each through a distance determined by the pin set thereon, said pins being in alinement just prior to the completion of the movement of the actuating means, and a bar movable transversely into 80 engagement with the alined pins, to prevent overthrow of the actuating means at the completion of their movement. 85

7. In a computing machine, the combination with computing wheels, of rack bars for 90 driving said computing wheels, a power shaft for driving said rack bars, a general operator driven by said power shaft for so driving them, pins settable on said rack bars to be engaged by said general operator for 95 driving the rack bars, a stop normally in ineffective position, and means for raising said stop to effective position as the pins engaged by the general operator approach it to cause said stop to arrest said rack bars by said 100 pins.

8. In a computing machine, the combination with bars having pins settable thereon, of computing wheels driven by said bars, a general operator for driving said bars concomitantly, and means for always simultaneously arresting all of said bars by the 105 pins set.

9. In a computing machine, the combination with numeral wheels and rack bars for turning them, of a stop for said rack bars, arms carrying said stop, a shaft on which said arms are mounted, a general operator for driving said rack bars, and a cam on said operator for operating said shaft. 110

10. In a computing machine, the combination with computing wheels, of rack bars comprising settable pins, a general operator for driving said rack bars by said pins to turn said wheels, a cam on said operator, and a stop for arresting said rack bars and operable by said cam. 115

11. In a computing machine, a register, and means for actuating the same, including preliminary representation devices, and an operating carriage for rendering the set preliminary representation devices operative on 120 said register, in combination with a movable stop device, operative on said preliminary representation devices, at the limit of the 125 130

register actuating movement of said operating carriage, to prevent over-rotation of the register, substantially as described.

12. In a computing machine, a register, and means for actuating the same, including preliminary representation devices, and an operating carriage for rendering the set preliminary representation devices operative on said register, in combination with a normally ineffective stop device, and means for rendering said stop device effective for operation on the said preliminary representation devices, at the limit of the register actuating movement of said operating carriage, to prevent over-rotation of the register, substantially as described.

13. In a computing machine, a register, and means for actuating the same, including register bars having key-set unit pins, and an operating carriage for rendering said register bars operative on said register, in combination with a unit pin stop, and means whereby said stop is thrown into a pin intercepting position, at the extreme limit of the register actuating movement of said operating carriage, to prevent over-rotation of the register, substantially as described.

14. In a computing machine, a register, and means for actuating the same, including preliminary representation devices, and an operating carriage for rendering the set preliminary representation devices operative on said register, in combination with a vertically movable stop blade, and a cam on said carriage operative to move said stop blade into a position to intercept the movements of the set preliminary representation devices, at the limit of the register actuating movement of said operating carriage, substantially as described.

15. In a computing machine, a register, and means for actuating the same, including register bars, having key-set unit pins, and an operating carriage for rendering said register bars operative on said register, in combination with a vertically movable unit pin stop blade, and a cam on said carriage operative to raise said stop blade into a pin intercepting position at the limit of the register actuating movement of said carriage, substantially as described.

16. In a computing machine, a register, and means for actuating the same, including register bars, having key-set unit pins, and an operating carriage for rendering said register bars operative on said register, in combination with a pivoted bail having a cam arm and a stop blade, and a cam on said carriage operative on said cam arm to raise the stop blade of said bail into a pin intercepting position, at the limit of the register actuating movement of said carriage, substantially as described.

17. In a computing machine, the combination, with computing wheels, individual drivers therefor, and operating means for said drivers; of pins settable on said drivers to determine the extent of rotation of said wheels by said drivers; a stop engageable with the set pins to positively arrest said drivers, said stop normally out of the path of said pins; and means to enable such engagement between said stop and the set pins to take place.

18. In a computing machine, the combination, with computing wheels, individual drivers therefor, and operating means for said drivers; of pins settable on said drivers to determine the extent of rotation of said wheels by said drivers; a stop engageable with the set pins to positively arrest said drivers, said stop normally out of the path of said pins; and means for shifting said stop into the path of the set pins, to enable such engagement to take place.

19. In a computing machine, the combination, with computing wheels, individual drivers therefor, and operating means for said drivers; of pins settable on said drivers to determine the extent of rotation of said wheels by said drivers; a stop engageable with the set pins to positively arrest said drivers, said stop normally out of the path of said pins; and means actuated by said operating means for shifting said stop into the path of the set pins, to enable such engagement to take place.
